CONTAINER FORMING MECHANISM

Martin Heres, Elmhurst, N. Y., assignor to
Eppens, Smith Company, Inc., New York, N. Y.,
a corporation of New Jersey

Application March 17, 1939, Serial No. 262,352

7 Claims. (Cl. 93—3)

In a generic sense this invention relates to the packaging of materials, and more particularly concerns an improved method and apparatus for packaging any commodity which may be desirable to put up in predetermined quantities.

More especially, the invention has to do with packaging of the commodity, tea, and in contradistinction to the conventional gauze fabric, paper, which is characterized by appropriate qualifications, is employed. Paper suitable for this purpose must be economical, light, somewhat flimsy, and at the same time tough and possess a relative degree of density. Of these prerequisites, that of density of the stock plays an especially important part. The minute interstices of the paper should preclude seeping through of the extremely fine sediment or dust which is present in all tea bags, but care must be exercised that the complete bag is almost totally devoid of undue overlapping of large folds, otherwise, owing to the presence of the very stock designed to occlude passage of the tea-dust or sediment, a series objection ensues—infusion is impeded.

Besides forming a bag which meets the foregoing requirements, I have also provided for the elimination of what is known as an "open bag", as well as, reduced to a minimum the likelihood of any clogging of the machinery, due to protruding bag ends of excessive length. Then, too, I have devised a novel means for maintaining the bag-forming blanks level as they are fed to the forming die.

This application is a continuation in part of applicant's copending application No. 229,061 for a container forming mechanism, filed September 9, 1938.

In the drawings, Fig. 1 is an elevation of the essential parts of a conventional type of packaging machinery illustrating an adaptation of the invention.

Fig. 2 is a perspective view of the supporting plate and the lower extremity of the plunger, the bag-forming blank being shown in dotted lines.

Fig. 3 is a top plan view of the supporting plate, plunger and blank, the plunger being in transverse section.

Fig. 4 is an enlarged view of the hopper, plunger and gripping devices assembly.

Fig. 5 is a detail elevation of the lower extremity of the plunger, supporting plate and gripping devices, the latter being shown in the position of closing the bag, and

Fig. 6 is a perspective view of the complete bag.

Because the present invention relates to the

forming die or supporting plate, the plunger or depressing element and the bag-forming opening, together with the manner of forming the container from the blank of bag material, it is not deemed necessary to illustrate and describe the complete packaging machinery. Only those parts as are required for a complete understanding of the invention are shown.

Referring more particularly to the drawings, 5 is the supporting plate designed to receive a blank 10 of paper 6, shown in dotted lines in Fig. 2. This paper is fed from roll 7 which passes over tension roll 8, and between a pair of superimposed rolls 9 and 10. It is severed by the knife 11 and presented upon the plate 5 as a square blank with 15 four corners 12.

13 is the hopper through which the commodity tea is fed in any suitable manner. Depending from, and preferably an integral part of the hopper is tubular plunger 14. This is uniformly 20 corrugated or fluted exteriorly and longitudinally, as at 15. Directly in the path of the plunger, plate 5 is provided with a substantially circular opening or forming die 16, the inner wall of which is mutilated, that is to say, the inner 25 wall has pairs of projections 17 in close proximity to each other with a relatively small recess 18 intermediate each pair of projections, and a larger recess 19 between the respective pairs of projections—the projections and recesses being 30 equidistantly spaced, symmetrically arranged, and in cross section as best seen in Fig. 3, somewhat simulates a quatrefoil. It will be also noted, particularly in Fig. 2, that the large recesses are aligned with corners 12 of the bag-forming blank 6, or the points which are furthest away from the center of the blank and between which the area of paper is greatest. So 35 as the plunger depresses the blank through opening 16, the excess paper invariably passes through large recesses 19, while the intermediate shorter portions of the blank are simultaneously constrained between the pairs of projections 17 and companion recesses 18, and due also to the combined effect of corrugations 15 of the plunger—40 which are complementary with respect to the said projections and recesses—the bag emerges 45 below plate 5 with a minimum of narrow folds 20, and evenly disposed bag ends 21, ready to be bunched by the gripping jaws 22 and 23.

By virtue of the narrow expandable folds, and reduction of overlapping of the folds, boiling water is enabled to instantly penetrate the bag and produce an accelerated brewing of the tea. Also, the infusion is free from dust, or the like 55

disagreeable sediment. And even formation of the bag ends eliminates "open bags", and clogging of the gripping jaws.

To insure guiding of the bag-forming blank in its travel, I preferably mount an annular collar 24 on the bottom of plate 5.

The paper used is light and flimsy, and when the supply on the feed roll 7 is low, it has a tendency to curl. Or a sudden gust of wind may blow a blank from plate 5. These contingencies are avoided by mounting on the plate a pair of lateral, inclined flanges 25 which serve to keep the blanks level and flat against the plate.

I claim:

- 15 1. In a bag-forming and filling machine, in combination, a forming die having an opening with a mutilated edge, a plunger with a uniformly corrugated exterior and movable to force a bag-forming blank through said opening and present a bag with relatively narrow folds, and gripping members beneath said die and opening designed to engage the folds at the mouth of the bag and effect a bunch thereof.
- 20 2. In a bag-forming and filling machine, in combination, a forming die having an opening with an irregularly notched edge, a plunger with a uniformly corrugated exterior and movable to force a bag-forming blank through said opening and present a bag with relatively narrow folds, and gripping members beneath said die and opening designed to engage the folds at the mouth of the bag and effect a bunch thereof.
- 25 3. In a bag-forming and filling machine, in combination, a forming die having an opening with a mutilated edge, a guide depending from said die in line with the opening therein, a plunger with a uniformly corrugated exterior and movable to force a bag-forming blank through said opening and present a bag with relatively narrow folds, and gripping members beneath said die and opening designed to engage the folds at the mouth of the bag and effect a bunch thereof.
- 30 4. In a bag-forming and filling machine, in combination, a supporting member including a forming die, a pair of inclined flanges carried by said member for maintaining a bag-forming blank substantially flat, the space between the flanges and the member being greater at the blank-receiving ends, a plunger movable to depress a blank through said opening, means for introducing loose material to within the bag, and means for closing the mouth of the bag.
- 35 5. In a bag-forming and filling machine, in combination, a supporting member including a forming die, a pair of edge guides carried by said member and having inclined overhanging flanges for maintaining a bag-forming blank substantially flat, a plunger movable to depress a blank through said opening, means for introducing loose material to within the bag, and means for closing the mouth of the bag.
- 40 6. In a bag-forming and filling machine, in combination, a supporting member including a forming die having an opening, the edge of which is formed with relatively large and small notches, the small notches being between the large notches, a plunger with a corrugated exterior and movable to depress a blank through said opening, means for introducing loose material to within the bag, and means for closing the mouth of the bag.
- 45 7. In a bag-forming and filling machine, in combination, a supporting member including a forming die having an opening, the edge of which is formed with large notches and intermediate small notches, said large notches designed to be aligned with the corners of a bag-forming blank, a corrugated plunger movable to force the blank through said opening and present a bag with narrow folds, and gripping members beneath said die and opening designed to engage the folds at the mouth of the bag and effect a bunch thereof.

MARTIN HERES.
